William F. Ramige,
By Frank S. Adleman

Attorney

UNITED STATES PATENT OFFICE.

WILLIAM F. RAMIGE, OF ROCKWELL CITY, IOWA.

TRACE CARRIER.

Application filed October 5, 1923. Serial No. 666,737.

To all whom it may concern:

Be it known that I, WILLIAM F. RAMIGE, a citizen of the United States of America, and resident of Rockwell City, in the county 5 of Calhoun and State of Iowa, have invented certain new and useful Improvements in Trace Carriers, of which the following is a specification.

This invention relates to trace holders for 10 harness, and has for an object the production of a trace holder adapted to be used in connection with the so-called Concord harness as now commonly made.

It is a further object of this invention 15 to produce a trace carrier of the character indicated, having means for the attachment of harness straps combined with the trace carrier, the same comprising a frame integral with the trace carrying device and 20 preferably formed of a single piece of material by the casting processes, whereby the device can be made inexpensively while at the same time it will prove efficient and satisfactory in use.

25 Another object of this invention is to produce a frame to which the harness straps can be connected, and a supplemental frame integral therewith having bearings in which a member is partially rotatable, 30 the said member having springs coacting with a part of the supplemental frame whereby they act as retaining devices for holding the traces in place.

With the foregoing and other objects in 35 view, the invention consists in the details of construction, and in the arrangement and combination of parts to be hereinafter more fully set forth and claimed.

In describing the invention in detail, 40 reference will be had to the accompanying drawings forming part of this application wherein like characters denote corresponding parts in the several views, and in which—

45 Figure 1 illustrates a view in perspective of a trace holder embodying the invention;

Figure 2 illustrates a perspective view of a slightly modified form thereof; and

50 Figure 3 illustrates a perspective view of the spring and its carrier.

In these drawings 5 denotes the body or frame which may be approximately round or elliptical, the said frame constituting an anchorage for harness straps such as 6. A 55 supplemental trace carrying frame is formed integral with the first mentioned frame,

and in the present embodiment of the invention, the supplemental frame is connected to the first mentioned frame by lugs 7, each having a recess 8 at its inner edge forming a seat for the bar 9, which bar has a rounded surface contacting with the seat in order that the bar may partially rotate, as will presently appear.

The bar 9 has a spring 10 extending 65 through it and each end of the spring bears against a hook or lug 11 which depends from the supplemental frame. The pressure of the spring against the lugs is sufficient to retain the traces 12 against accidental 70 displacement after they have been inserted in the holder by depressing the spring to a degree which will permit the insertion of the trace between the spring and the lug.

The lugs 11 preferably extend to or below 75 the plane of the upper surface of the frame or body 5 so that when a trace extends over the frame or body 5 and engages the lugs, it is approximately parallel with the axis of the body or frame 5. When the trace is 80 thus held, there can be no appreciable pressure exerted by it on the springs and the traces are not apt to displace the springs to a degree that will release the traces.

The supplemental frame has two parallel 85 and approximately horizontal portions 13 and 14 that are raised with respect to the lugs and the frame 5, and each is connected to or formed a part of the lugs 7 by reason of the fact that each portion 13 and 14 90 has depending ends 15 terminating in inwardly disposed extensions that are connected to or formed integral with the lugs 7, as stated. The lugs 11 are preferably formed equidistantly from the depending 95 portions and the clearance therebetween is sufficient to permit the insertion of a trace in order that it may be lodged and held in the manner stated. The frame 5 has appropriate loops 16 to which harness straps 100 may be connected and these, of course, are formed integral with the frame in the interests of minimizing the cost.

In the modification shown in Fig. 2, the frame 17 has a supplemental frame 18 105 therein in raised position as compared with the position of the frame 17, and the supplemental frame is supported by the posts or legs 19 that are integral with the two frames. Two opposed elements of the 110 supplemental frame have lugs 20 that engage an end of a spring 21 secured to the

bar 22 that oscillates in bearings 23 formed integral with the supplemental frame, and this relation of parts permits the portion of the spring to one side of the bar to yield slightly when a trace is being inserted between a lug and the spring at its opposite end, the yielding action thus produced permitting the bar to partially rotate in the bearings so that there is no strain on the 10 bar which would tend to fracture it.

A further advantage of this invention is that if the spring or bar become impaired, another element may be substituted, and hence by the removal of this very small 15 part of the whole construction, the device can be maintained in an efficient state at comparatively small cost.

I claim:

1. In a trace holder, a frame constituting 20 an anchorage for harness straps, lugs within the area of the frame having recesses forming bearings, parallel supplemental frame members supported in spaced relation to each other from the said lugs, downwardly 25 extending trace-engaging elements on the

said parallel portions of the said supplemental frame, a bar rotatably mounted in the bearings of the lugs, and a spring having its ends extending laterally of the said bar into engagement with the ends of the trace-engaging elements. 30

2. In a trace carrier, a frame adapted to form anchorages for harness straps, a supplemental frame within the area of the first mentioned frame, means for rigidly connecting the two frames, bearings at opposite sides of the supplemental frame, lugs constituting trace-engaging elements extending downwardly from parallel sections of the supplemental frame standing at 35 right angles to the first mentioned sections of the supplemental frame and terminating at or below the plane of the upper edge of the first mentioned frame, a member rotatable in the bearings, a spring extending through the said member and into engagement with the lugs, substantially as described. 40

WILLIAM F. RAMIGE. 45
